S. J. ROGNLIE

PHONOGRAPH

Filed June 30, 1922

Fig. 1.

Fig. 2.

UNITED STATES PATENT OFFICE.

SEVERIN JOEL ROGNLIE, OF LEWISTOWN, MONTANA.

PHONOGRAPH.

Application filed June 30, 1922. Serial No. 571,993.

To all whom it may concern:

Be it known that I, SEVERIN J. ROGNLIE, a citizen of the United States, and resident of Lewistown, in the county of Fergus and State of Montana, have invented certain new and useful Improvements in Phonographs, of which the following is a specification.

This invention relates to phonographs and the subject matter of this application is 10 disclosed in my United States Patent #1,420,668.

In the phonographs now in general use the tone is usually subdued by closing the shutters which extend across the horn and 15 these shutters when in their open position greatly detract from the clearness of the reproduced tones, and it is therefore, an important object of this invention to provide novel means whereby the tones may be subdued without the employment of these 20 shutters.

By the use of the improved phonograph the effect of distance is given to the reproduced tones and a softer and more pleasing tone is provided, all of which adds to the 25 desirability of the phonograph.

Further, the invention forming the subject matter of this application aims to provide novel means whereby the auxiliary horn 30 may be readily and conveniently attached to the phonograph.

A further object is to provide a phonograph which is of highly simplified construction, neat in appearance and cheap to 35 manufacture.

Other objects and advantages will be apparent during the course of the following description.

In the accompanying drawing forming a 40 part of this application and in which like numerals are employed to designate like parts throughout the same,

Figure 1 is a perspective of a phonograph 45 constructed in accordance with this invention, parts being broken away to illustrate the auxiliary horn,

Figure 2 is a detail sectional view through 50 the phonograph, the view illustrating the means employed to attach the auxiliary horn.

Figure 3 is a perspective of an attaching member embodied in the invention.

In the drawing wherein for the purpose 55 of illustration is shown a preferred embodiment of the invention, the numeral 5 designates the casing of a phonograph, while the

numeral 6 designates a concealed horn, the sides of which are arranged at the side walls of the casing or cabinet.

Figure 1 illustrates that a combined sound 60 board and closure 7 is hinged at its rear edge as indicated at 8 to the rear side of the concealed horn 6 and the sound board forms a convenient means whereby the volume of the sound from the concealed horn 65 65 may be regulated.

As in the case of the aforesaid application, the sound board 7 has connection with a plurality of flexible elements 10 trained about pulleys 11 mounted on a shaft 12. 70 The shaft 12 extends transversely through the cabinet and is formed at one end by a crank 13 by means of which the pulley 11 may be rotated for raising or lowering the 75 sound board 7.

Figure 1 further illustrates that the phonograph is provided with a tone arm 16 which has communication with the concealed horn 6 and conducts the reproduced sounds to the horn.

A coupling member 20 is mounted between the tone arm 16 and the concealed horn 6 and is provided with a valve 22. When the valve 22 is in the position illustrated in dotted lines in Figure 2 the sound waves do not travel through the concealed horn but enter the upper attaching section 26 of an auxiliary horn generally described by the numeral 27. On the other hand when the valve 22 is in its full line position as illustrated in Figure 2 the sound waves are conducted through the concealed horn.

In carrying out the invention the shaft or pivot element 23 is extended out through one side of the cabinet and is provided with an actuating member or pointer 30 which may be manually turned for positioning the valve 22 as desired. As illustrated in Figure 1, one side of the cabinet is provided with a dial 33 over which the pointer 30 plays and it will be seen that the dial and the pointer form a convenient means for accurately indicating the position of the valve 22.

Considering Figures 1 and 2 it will be observed that the auxiliary horn 27 arranged in the rear of the horn 6 has its lower end flared and provided with an outlet box 38 extended through the back of the phonograph and having its exposed side 105 apertured as indicated at 40 for the discharge of the tone waves.

In operation if it is desired to produce a soft mellow tone having the effect of distance the sound waves are directed to the long narrow auxiliary horn 27 and the tone waves are discharged through the apertures 40. The tones thus discharged through the apertures 40 are more or less free from the shrilled or high notes and the tones are free from other defects highly noticeable in the ordinary phonograph. Specifically the scratching sounds so noticeable in the phonographs now in use are almost entirely eliminated.

The clearer reproduction of the sounds is generally accounted for by the fact that the sound is not choked off at the tone arm or by means of the shutters ordinarily employed.

With reference to the foregoing description taken in view of the accompanying drawing it will be apparent that a phonograph constructed in accordance with this invention does not differ radically in appearance from the phonograph now in the market, and therefore, the invention will not be prejudiced when placed upon the market.

The improved auxiliary horn consists of an upper section 26 and a lower section 44 jointed to the upper section by means of a coupling member 46. The tone arm may be readily connected to the valve casing 20 by means of a U-shaped attaching member 50 preferably formed from spring metal. The spaced parallel side arms of the U-shaped attaching member are arranged on opposite sides of the auxiliary horn and the casing 20 and are formed with notches 55 which partially receive attaching pins 56 carried by the casing. The forward portions of the arms of the U-shaped member 50 have their upper sides formed with notches 57 to partially receive attaching pins or lugs 58 arranged below and in advance of the lugs 58.

In attaching the auxiliary horn to the casing 20 the bight portion of the U-shaped member 50 is engaged with a rear side of the horn and is received within a notch 60 carried by an attaching bracket 61. The arms of the U-shaped member are now arranged on opposite sides of the casing and are engaged with lugs 56 and 58 in the

manner illustrated in Figure 2 so that the resiliency inherent in the U-shaped member will force the horn flatly into contact with the open side of the casing so as to positively prevent the escape of sound waves, a gasket 63 is located between the casing 20 and the auxiliary horn.

By the use of this invention the tone may be readily and conveniently varied according to the desire of the operator by simply rotating the pointer 30 over the dial 33, and as previously stated tones of a very superior quality are reproduced.

It is to be understood that the form of the invention herewith shown and described is to be taken as a preferred sample of the same and that such novel changes in arrangement and description of parts may be made as will remain within the spirit of the invention and the scope of what is claimed.

I claim:

1. A phonograph having a sound conduit forming part of a sound passage and being provided with a lateral opening, a horn having an attaching section provided with a corresponding opening, and means for holding the section in place upon the conduit when the openings are in registration, said means including pins carried by the conduit, a U-shaped member extending around said section to the sides of the conduit and having oppositely disposed notches to engage the pins, and thereby retain its position, and means including a bracket carried by the section beneath which said member engages.

2. A phonograph having a conduit forming part of a sound passage and being provided with a lateral opening, a horn having an attaching section to be fitted against the conduit and having a corresponding opening, resilient means bent to embrace the attaching section and extend along the sides of the conduit, said means having oppositely positioned notches, pins carried by the conduits to engage said means on opposite sides and in the notches, and means on the attaching section beneath which a portion of said bent means is positioned to aid in supporting the attaching section in place.

SEVERIN JOEL ROGNLIE.
